UNITED STATES PATENT OFFICE

CARL SCHWARTZ, OF ELKHART LAKE, WISCONSIN, ASSIGNOR TO BRANDT AUTOMATIC CASHIER COMPANY, OF WATERTOWN, WISCONSIN, A CORPORATION OF WISCONSIN

COIN SORTING MACHINE

Application filed July 23, 1925. Serial No. 45,573.

This invention relates to coin sorting machines.

This invention is an improvement over that disclosed in United States Patent Number 1,526,762 for coin sorting machines issued to me February 17, 1925, and has the same general objects as those set forth in such application.

In coin sorting machines which employ a selector disk and a distributor or mechanism for receiving coins from the selector in a synchronous manner, difficulty has been experienced in properly timing the parts and in maintaining the timing when the machine becomes wedged or even slightly jammed. When this occurs, the timing is disturbed and the machine does not function properly.

This invention is designed to overcome the above noted defects, and objects of this invention are to so construct and associate the selector disk and distributor that absolute synchronism is maintained at all times even under abnormal conditions and to provide a machine in which jamming cannot occur.

Further objects are to provide a coin sorting machine which will receive the coins in a haphazard manner, which will automatically and rapidly sort the coins, which has a yielding drive to avoid undue stresses even under abnormal conditions, and which is quick and accurate in operation.

Further objects are to simplify the construction of coin sorting machines and to provide a machine which has a relatively small number of parts each of which is of sturdy and substantial construction and not likely to get out of order.

An embodiment of the invention is shown in the accompanying drawings, in which:—

Figure 1 is a vertical sectional view through the machine.

Figure 2 is a plan view of the hopper and the associated parts, such view being partly in section.

Figure 3 is a view of the machine with the selector disk removed and with the plate over the distribution chutes removed.

Figure 4 is an edge view of the distributor,

such view showing the distributor in an inverted position.

Figure 5 is a bottom view of the distributor.

Figure 6 is an edge view of the distributor and selector disk and associated parts, such view being fragmentary and a development of the distributor.

Figure 7 is a perspective view of a portion of the sorting member.

Figure 8 is a view of the slide with the hopper broken away.

Figure 9 is a sectional view on the line 9—9 of Figure 2.

Figure 10 is a fragmentary view of a portion of the hopper with the clamping bolt removed.

Figure 11 is a fragmentary view of the ring which is interposed between the sorting disk and the distributor.

As shown in Figure 1, the machine comprises a tilted hopper. This hopper has a cylindrical wall and a bottom wall 2 arranged in a slanting manner, as illustrated particularly in Figure 1. Within the hopper a distributor 3 is mounted and a selector disk 4 is directly attached by means of screws or other members to the upper end of the distributor so that the selector disk and distributor form a unitary structure.

An annular ring 5 is interposed between the distributor 3 and the outer portion of the selector disk and projects between the portion of the selector disk which overhangs the pockets in the distributor, as will be described in greater detail hereinafter. The ring 5 is seated upon a shoulder 6 formed in the hopper 1 and is held in place by means of the removable portion 7 of the hopper. This removable portion is attached to an outer ring 8 and, as shown particularly in Figures 2 and 9, a pair of tie bolts 9 extend through notches in this ring and through notches formed in ears 10' of the hopper 1. Preferably, a pair of tie bolts 9 are provided and are located upon opposite sides of the hopper, as shown in Figure 2, so that loosening of the tie bolts will permit ready removal of the parts of the machine.

It is to be noted from Figure 1 that the hop-

per is provided with an upwardly projecting portion 10 which extends around its lowermost side. This upwardly projecting portion carries an annular slide 11 which is mounted inside of the hopper which is shown particularly in Figures 1 and 2. Preferably, the slide 11 is held in contact with the inner sides of the hopper by means of a spring 12 which has its ends fastened to the slide, and which is hooked beneath a projecting member or hook 13 rigidly carried by the hopper extension 10. In this manner, the slide is drawn against the sides of the hopper and also is urged downwardly in a yielding manner, such slide being free to move upwardly in case the coins crowd below the slide to a sufficient extent.

It is to be noted, particularly, that the lower face of the slide 11 is beveled, as indicated at 14, so that coins thrown into the hopper in a haphazard manner and contacting with the curved face of the slide will travel downwardly, and will lie against the beveled face 14 of the slide as they pass the lower edge, and will thus be presented to the selector disk 4 in a flat manner. However, if the coins should bunch beneath the slide 11, it will freely move upwardly and relieve this congested condition.

30 The selector disk 4 is provided with a plurality of notches 15 in its outer edge which are adapted to receive a single coin selected from the hopper, such notches being of a size to hold a coin of any denomination which is handled by the machine. These coins rest upon the ring 5 and are swept around by the disk 4, such disk rotating in the direction of the arrow shown in Figure 2.

40 The coins are prevented from lodging in pairs, one above the other, in the notches of the selector disk by means of a spring urged projecting finger 16. If desired, this finger may be provided with a small roller at its lower side, as indicated in Figure 2.

45 It is to be noted from Figure 2, that the finger 16 projects through a slot in the wall of the hopper 1 and is urged by means of a spring 17 inwardly, the outer end of the finger being pivoted to the adjacent portion of the hopper, as shown in Figure 2. This finger is spaced upwardly a slight distance from the selector disk 4 and permits a single coin to ride beneath it. However, if two coins are lodged, one above the other, it will dislodge the upper coin. Further than this any crooked coin of too great a distortion to be conveniently handled by the machine is dislodged by the finger 16. In addition to this, however, it is to be noted from Figure 2 that 50 the coins in the lower portion particularly, of the hopper and along the sides, will roll against the sides of the hopper as they are swept around by the selector disk 4. Thus a crooked coin will very quickly work out of 55 the notch 15 in the selector disk. However,

if this does not occur, the finger 16 will remove such coin.

In the upper portion of the hopper, a shield plate or guard plate 18 is provided, as shown in Figures 1 and 2. This guard plate is 70 spaced a slight distance above the selector disk 4 and prevents coins from dropping through the aperture 19 formed in the annular ring 5, as shown particularly in Figure 11. It is to be noted from Figures 1 and 2 that the opening 19 through the ring 5 is located immediately below the guard plate 18.

75 Coins swept around by the selector disk 4 will ride upon the face of the ring 5 and when they arrive at the opening 19 will drop through such opening in a single manner and into the pockets 20 of the distributor 3. Such pockets are most clearly shown in Figure 6 and it is to be noted that they are provided with a slanting face, as shown at 21 80 on the upper portion of their trailing sides and are provided with a vertical face 22 on the leading side.

85 The bottoms of the pockets 20 are provided with straight portions 23 within which the 90 coins are adapted to stand, as shown in the left hand portion of Figure 6.

95 From reference to this figure, it will be seen that as the coins are swept along the ring 5 they arrive at the opening 19 and slide through such opening into one of the pockets 20.

100 It is to be noted particularly that as the coins tilt in the openings 19, they fall upon the slanting faces 21 of the pockets, as indicated in the central portion of Figure 6. This slanting face 21 guides the coins into the vertical portion 23 and thus causes such coins to assume a vertical position. In this connection, it is to be noted that a pocket 105 20 is positioned beneath each of the notches 15 in the selector disk 4 and thus there can be no variation in the synchronism of the operation of the selector disk notches and the pockets in the distributor as the selector disk 110 and the distributor together form a unitary structure.

115 The coins standing on edge are swept around the annular channel-like ring 24 (see Figures 1 and 7) which is carried within the hopper and which seats against the side faces of the hopper and against the bottom thereof. The lowest portion of this channel-like member 24 is provided with cutouts 25 arranged in a stepped manner and of different widths corresponding to coins of different dimensions. This member 24 is in reality an angle iron in cross section and the vertically positioned coins thus rest within the channel and are slid along such channel by means of the distributor 3. When they arrive at their proper sized opening 25 in the member 24, they drop through at such point and enter the appropriate slot or chute 26 formed in the sorting head 27 of the ma- 120 125 130

chine, as shown most clearly in Figure 3. This sorting head is bolted directly to the base 2 of the hopper and to a support 28 (see Figure 1) which carries the coin receiving trays 29. The sorting head 27 is provided with a removable cover plate 30, as indicated in Figure 1, to give free access to the interior of such head when needed.

The driving mechanism for the machine is extremely simple as it is only necessary to drive the unitary structure consisting of the distributor 3 and the selector disk 4.

As shown in Figure 1, a relatively large fiber gear 31 is mounted upon a projecting lower hub formed as an integral portion of the distributor 3. It is urged against a metal washer 32 positioned adjacent the distributor 3 by means of a plurality of leaf springs 33 whose curved outer ends bear against a correspondingly curved annular portion of the fiber gear 31. These springs 33 are removably held in position by means of screws 34 which pass through such springs and into the base of the distributor 3. Thus a yielding drive is provided for the distributor in a very simple manner which permits relative sliding between the distributor and the gear 31 under abnormal conditions. The gear 31 meshes with a small pinion 35 carried by a short shaft 36 projecting through the base 2 of the hopper. The lower end of the shaft 36 carries gear 37 which meshes with the driving pinion 38 of an electric motor 39. This electric motor is mounted upon a slanting bracket 40 which continues to the hopper and supports the hopper, as shown in Figure 1. The lower end of this bracket is supported by means of a standard 41 projecting upwardly from the base 42 of the machine.

From reference to Figure 1, it will be seen that a very rigid support of a simple nature has been provided which, as just described, consists of the standard 41 extending upwardly from the base and holding bracket 40 of the motor. This bracket in turn is rigidly attached to the hopper and the hopper is attached by means of the distributor head 27 to a bracket 28 at the forward portion of the machine, such bracket in turn being carried by means of one or more uprights 43 projecting upwardly from the base 42.

In order to insure the correct centering of the distributor 3, it is mounted upon a shaft 44 which is carried within an elongated bearing indicated generally at 45. This elongated bearing insures a correct positioning of the distributor and of the selector disk 4 and preferably such shaft is provided with a shoulder to aid in the correct positioning of the distributor, as shown in Figure 1.

In operation, coins are dumped in a haphazard manner into the hopper and falling against the slide 11 are turned and presented in a flatwise manner to the selector disk 4.

This selector disk rotates and carries the coins within its notches 15 to the opening 19 in the ring 5. As this point the coins fall into the distributor pockets 20 and are stood on edge within the channel member 24 of the hopper. They are swept around by the distributor and fall through their appropriate sized openings in the cutaway portion 25 of the sorting member, as shown in Figure 7. From this point they pass into their correct chutes 26 in the distribution head and from thence pass into the appropriate removable tray 29.

From actual practice with this machine, it has been found that the machine is very accurate in operation and is extremely rapid. It has also been found that it is very quiet in operation and is free from any easily damaged parts which are likely to get out of order.

From actual tests conducted with this machine, it has been found that the machine can run continuously for any length of time and will, as stated above, rapidly and accurately sort coins furnished such machine, in a haphazard manner.

It is to be noted that the machine is of extreme simplicity and has a very small number of parts in comparison to the operations performed by the machine. Further, it is to be particularly noted that the machine is fool proof for all practical purposes.

Although the invention has been described in considerable detail, it is to be understood that the invention may be variously embodied and is, therefore, to be limited only as claimed and it is expressly understood that the term "ring", applied to the element 5 in the claims, covers a flange, plate or other equivalent.

I claim:

1. In a coin sorting machine including a hopper adapted to receive coins, a ring within said hopper and having an opening therethrough, a selector disk having coin receiving pockets and rotatably mounted above said ring, a distributor mounted within the hopper and below said ring and having pockets corresponding to those in said disk, and a sorting member mounted below said distributor and having apertures therethrough of different widths to receive coins of different denominations.

2. In a coin sorting machine including a hopper adapted to receive therein coins, a ring carried within said hopper and having an opening therethrough, a selector disk having pockets for receiving the coins and rotatably mounted above said ring, a distributor mounted below said ring and having pockets corresponding to those in said disk, and a sorting member mounted below said distributor and having apertures therethrough of different widths corresponding to coins of different denominations, said distributor and said selector disk being rigidly connected.

3. A coin sorting machine comprising a distributor having a series of pockets opening through its upper and lower face, a tilted hopper within which said distributor is revolvably mounted, a notched disk carried upon and secured to the upper face of the distributor, and overhanging the upper ends of the pockets, an annular ring carried by said hopper and located between the overhanging portion of said notched disk and the adjacent portion of said distributor, said ring having an opening through which coins may pass from the notched disk to the distributor, and a sorting member mounted below said distributor and having openings therethrough for coins of different denominations.

4. In a coin sorting machine including a hopper having a slanting bottom and having a sorting member in communication therewith, said sorting member having apertures therethrough for coins of different denominations, a distributor mounted within said hopper and having pockets therethrough for the reception of coins, an annular ring covering the upper ends of the pockets and having an opening therethrough, a notched plate secured to said distributor and over-riding said ring, and said notched plate adapted to move the coins within said hopper to the opening within said ring.

5. A coin sorting machine comprising a tilted hopper having an upper portion and a lower portion held together by removable tie bolts and provided with a sorting member at its lowest side, said sorting member having apertures of different widths for coins of different denominations, a distributor mounted within said hopper and having pockets therethrough for the reception of coins, an annular ring located above said distributor and having an opening therethrough, said ring being clamped between the upper and lower portions of said hopper and a notched disk revolvably associated with said distributor and mounted above said ring.

6. In a coin sorting machine comprising a hopper having therein a coin selector and a distributor rotatable in unison, a driving gear yieldably held to the under side of said distributor, and a driving pinion meshing with said gear.

7. In a machine of the class described, the combination of a casing and a coin sorting means in direct communication therewith, a distributor within said casing and adapted to convey coins to the sorting means, a coin selector fixed to said distributor, said selector and distributor having corresponding coin receiving pockets, a ring stationary with respect to said casing and positioned between said selector and distributor, and said ring controlling the passage of the coins from the selector to the distributor at a certain point prior to their discharge into said sorting means.

8. In a machine of the class described, the combination of a coin receiving hopper and a sorting means, a coin selector and a coin distributor within said hopper, said selector and distributor having corresponding coin receiving pockets, said distributor adapted to convey coins from said hopper to said sorting means, a ring stationary with respect to said hopper and adapted to permit the passage of coins from the selector to the distributor at a predetermined point, and said point being in advance of said sorting means, to permit the coin to position itself within the distributor pocket during the movement of the same for proper reception by the sorting means.

9. In a machine of the class described, the combination of a coin receiving hopper and a coin selector and distributing means therein, said selector and distributing means being provided with corresponding coin receiving pockets, and a guard plate carried by said hopper and overlying the pockets in said selector to prevent the reception of more than one coin at a time therein.

10. In a machine of the class described, the combination of a coin receiving hopper and a sorting means, a coin selector and a coin distributor within said hopper, said selector and distributor rotating in unison about an inclined axis, and releasable means connected to said distributor for rotating the same.

11. In a coin sorting machine including a hopper into which coins are haphazardly placed, a distributor revolvably mounted within the hopper, a selector revolvably mounted within the hopper and adapted to feed one coin at a time to the distributor, and means for driving the distributor and selector in unison.

In testimony that I claim the foregoing I have hereunto set my hand at Milwaukee, in the county of Milwaukee and State of Wisconsin.

CARL SCHWARTZ. 110
